UNITED STATES PATENT OFFICE.

ROLAND B. DAY, OF SWARTHMORE, PENNSYLVANIA, ASSIGNOR TO DAY'S PETROLEUM PROCESS CO., INC., A CORPORATION OF ARIZONA.

PROCESS OF TREATING HYDROCARBON OILS.

Application filed December 15, 1920. Serial No. 430,873.

To all whom it may concern:

Be it known that I, ROLAND B. DAY, a citizen of the United States, residing at Swarthmore, in the county of Delaware and State of Pennsylvania, have invented certain new and useful Improvements in Processes of Treating Hydrocarbon Oils, of which the following is a specification.

This invention relates to processes for producing hydrocarbon materials having low boiling points from hydrocarbon materials having high boiling points.

One object of the invention is to provide a process for cracking oils by which liquid oils are subjected to a continuous travelling and agitating movement within a closed chamber under conditions which reduce to a minimum the possibility of carbon formation on the chamber walls.

Another object of the invention is to provide a process in which there is a continuous travelling movement of the liquid oil from the cooler to the warmer parts of the apparatus so that materials requiring a lower degree of heat may be cracked and likewise materials requiring a higher degree of heat may be cracked by coming into contact with an increasing degree of heat during travel through the apparatus.

One feature of the invention relates to the agitating and continuous travelling movement of the oil which is effected by continuous rotation of a conveyor apparatus within tubes of a tubular retort and the cooperation of the conveyor apparatus with ball cleaner elements located within the tubular retort. The invention provides that the ball elements may be free to move, roll or tumble about during their passage through the retort tubes. When oil and the metal balls have been used in such tubes and propelled therethrough by screw conveyors, it has been found that substantially no carbon has been formed on the retort wall or on the conveyor screw. The reason for the low percentage of carbon formation may be ascribed to various circumstances and conditions, but is at least in part due to the agitation, travelling movement and frictional contact of the oil and freely movable metal balls within the retort tubes.

The process provides for a continuous movement of the oil through a series of tubular conveyor retorts, the removal from

the last retort, and the reintroduction of the oil into the first retort of the series.

The process is preferably conducted in the apparatus illustrated in the accompanying drawings, in which:

Figure 1 is a side elevation of the heating furnace illustrating the exterior drive shafts and showing the outlines of the tubular retorts in dotted lines;

Figure 2 is a view illustrating the relative direction of rotation of the conveyor shafts looking in the direction of the furnace on the section line 2—2 of Figure 1;

Figure 3 is a section taken on the line 3—3 of Figure 1 looking in the direction of the arrow and showing the position of the retort tubes in the furnace; and

Figure 4 is a view of the retort tubes with the furnace removed, illustrating the relative directional movement of the materials within the tubes and the movement of the metal balls.

Like reference numerals refer to like parts in the different figures of the drawings.

Referring in detail to the drawings of the apparatus which has been used satisfactorily in conducting the present invention, 1 represents the masonry construction, either concrete, stone or brick, but preferably fire brick, such as will stand severe temperatures. A suitable stack 2 is provided for leading off the furnace fumes, smoke, and gases of combustion. A source of heat is provided by burners 3 located at the lower part of the furnace and fed by suitable pipes 3^a providing liquid or gaseous fuel. The furnace is braced by suitable buck stays 1^a holding the same to a suitable masonry or concrete base. The flame and hot gases from the burner nozzles is projected inwardly and passed upwardly in the furnace, over a centrally positioned partition 4, and downward to ultimately escape through the stack 2. During the upward movement the heat comes into direct contact with the exterior of a plurality of longitudinally positioned retort tubes, as will be described.

The drawing illustrates three cracking tubes or retort tubes 5, 6 and 7, positioned one above the other and substantially horizontally. Within the tubes 5, 6 and 7 are respective screw conveyors 5^a, 6^a, and 7^a, mounted on and adapted to turn with shafts 5^b, 6^b, and 7^b, respectively. Suitable jour-

nal boxes or stuffing boxes are indicated for the respective shafts at 5^a, 6^a, and 7^a. Materials within the tube 5 are passed to the left, referring to Figure 4 and are dropped 5 through the communicating pipe 8 into the end of the tube 6, and similarly, such materials are passed in the opposite direction in the tube 6 and permitted to drop through the communicating pipe 9 to the lowermost 10 tube 7, in which latter the materials are again moved to the left. The direction of travel of the contents of the apparatus is indicated by arrows. Steel balls B are located between each of the flights of the 15 conveyor screws and are freely movable to roll or tumble during the passage of the oil and balls through the retort tubes, and move from the upper to the lower tube and by means of the elevator conveyor screw are 20 lifted from the lowermost retort tube 7 and reintroduced into the upper tube 5. It is necessary that the balls B be of high heat conductivity and that they resist the abrasive wear to which they are subjected 25 by the action of the conveyor screw in moving them through the apparatus. The use of steel balls has proved of advantage over other known forms. Material which will pulverize or abrade readily is undesirable be- 30 cause it will combine with the liquid oil, and particularly with the heavier residues thereof and adhere to the conveyor screw and tend to choke up the retort tubes. Steel balls have proved of advantage because of 35 their long life, the cleaning action on the interior of the retort tubes and screws, and because they may roll and tumble within the retort tubes without jamming. Any kind of metal balls would probably exercise 40 the necessary cleaning action, but steel balls combine the necessary hardness for long wear together with high heat conductivity.

Oil and steel balls B discharged from the left hand end of the tube 7 drop downwardly through the communicating pipe 10 into the tube of the elevator conveyor shaft 11, which latter has a conveyor screw 11^a mounted on a shaft 11^b in a manner similar to the mounting of the conveyor screws 5^a, 50 6^a, and 7^a. A stuffing box 11^c is also provided. At the lower end of the elevator conveyor screw tube 11 is a drain pipe 12 having a suitable valve 12^a and positioned substantially at the lowermost point of the 55 system. Materials raised through the tube 11 are moved to a point near the end of the tube where they are permitted to drop downwardly through the communicating pipe 13 into the extreme right hand end of the up- 60 per conveyor tube 5, from which point they are again passed through the apparatus.

At the top of the system of cracking and elevator tubes is positioned a large reservoir for oil which serves as a combined pre- 65 heating chamber, reservoir and expansion

chamber. This chamber is indicated by numeral 14, and is provided with an oil inlet pipe 14^a for the admission of untreated oil which may be controlled by a suitable valve 14^b. A series of test drain spigots 14^c 70 are mounted on the chamber at different elevations to determine the height of the oil therein. A pipe 15 at one end of the chamber 14 leads downwardly from the floor of the chamber to the cracking tube 5. At the 75 other end of the chamber 14 is a pipe 16 leading to the upper end of the conveyor tube 11. At the top of the expansion chamber 14 are suitable pipe connections leading to necessary condensers. At 17 is indicated a condenser line governed by a weighted valve. At 18 is indicated another condenser pipe which may lead to a reflux condenser, not shown.

Drive means for driving the shafts 5^b, 6^b, 85 7^b, and 11^b is provided by main drive shaft 19 mounted in suitable bearings 19^a, and driven by a pulley wheel 20, which latter may be operated from any suitable source of power. Referring to Figures 1 and 2, it 90 will be noted that the shaft 19 moves clockwise and turns a sprocket gear 21, which in turn operates a continuous chain 22, which latter extends over sprocket gears 11^d, 7^d, 6^d, and 5^d, which are mounted respectively 95 on the conveyor shafts 11^b, 7^b, 6^b, and 5^b. The arrows in Figure 2 indicate the relative direction of rotation of the sprocket wheels and the conveyor shafts.

Because of the incline of the conveyor 100 shaft 11^b, it is necessary to provide a universal joint in this shaft between the sprocket wheel 11^d and the stuffing box 11^c. This joint is indicated at 11^e in Figure 1, and the lower end of the shaft 11^b is journaled in a fixed bearing 11^f. At the upper 105 end of the conveyor elevator tube 11 is a corresponding universal joint supported by a fixed bearing 11^f, mounted on a bracket secured to the main furnace structure. A 110 second drive chain 22^a connects the opposite ends of the drive shaft 19 and the conveyor shafts 5^b, 6^b, 7^b, and 11^b.

The process has been satisfactorily conducted in apparatus like that described 115 above, in which the retort tubes 5, 6, 7 and 11 were of six inch bore, in which a conveyor screw five and three-quarter inches was operated. In conducting the process in the above described apparatus, oil is introduced into the expansion chamber 14 through the pipe 14^a, and from this chamber it circulates downward filling up the different tubes and elevator tube of the system. When the conveyor screws are actuated the oil moves downwardly through the tubes, and at the same time is subjected to the continuous agitating movement caused by the conveyor screw and the movement of the metal balls propelled by the 120 125 130

screw. The blast of flame from the burners 3 provides a temperature in the lower retort hotter than the temperature of the upper retort. Thus, when a temperature of 5 1000° F. is present in the lower retort, the temperature in the upper retort will probably be about 200° F. less, or about 800° F. The process includes a temperature range varying from 550° F. to 750° F. at the upper 10 per retort, and from 800° F. to 1000° F. for a maximum at the lower retort. The difference in temperature between the upper and lower tubes is accounted for in part by the distance from the source of heat, and by 15 the fact that fresh oil is introduced into the upper retort tube. This gradual heating has proved advantageous because every particle of oil is at some time within its travel, subjected to the degree of temperature best 20 suited for cracking it. Materials have been successfully treated and remarkably large yields of cracked products obtained when a temperature of 850° F. was used in the lower part of the apparatus, and at a pressure 25 of about 75 pounds per square inch.

The process provides for the removal of heavy residues from the lower part of the apparatus through the pipe 12. This withdrawal may be continuous or periodic. It is 30 believed that the coke or carbon which is formed during the passage of the oil through the retort tubes is for the most part withdrawn with the waste residues. The apparatus has proved remarkably free 35 from carbon deposits, and this may be ascribed in part to the cleaning action of the balls within the apparatus and to their freely movable rolling or tumbling movement which makes it possible for them to engage 40 the surface of the conveyor tube without travelling in any one fixed path. It is believed that the cooperation of the conveyor with the balls, thus serving as dual agitating means, makes it possible to bring a greater 45 proportion of the oil intimately into contact with the high heat conductivity of the balls, screw, and retort tube. This agitating movement in the oil is probably sufficient to churn the oil up into an emulsion which is 50 more readily cracked during the passage through the apparatus than ordinary oil would be if moving in a quiet undisturbed flow.

What I claim is:

55 1. The process of producing hydrocarbon oils having low boiling points from hydrocarbon oils having high boiling points which comprises subjecting the original oil to a continuous agitating movement within a closed chamber, causing a conveyor member within said chamber to move said oil and to propel freely movable metallic elements through said chamber, and subjecting said oil while in said chamber to a temperature 60 sufficient to effect cracking.

2. The process of producing hydrocarbon oils having low boiling points from hydrocarbon oils having high boiling points which comprises subjecting the original oil to a continuous agitating movement within a closed tubular chamber, causing a continuous movement of the oil lengthwise of a chamber, causing a screw conveyor within said chamber to move said oil and propel freely movable metallic balls lengthwise of said tubular chamber in contact with said oil, and subjecting the contents of said tubular chamber to a temperature sufficient to effect cracking. 75

3. The process of producing hydrocarbon oils having low boiling points from hydrocarbon oils having high boiling points which comprises subjecting the original oil to a continuous agitating movement within a closed chamber, causing a conveyor member within said chamber to move said oil and to propel freely movable non-absorbent elements of high heat conductivity through said chamber, and subjecting said oil and freely movable elements while in said chamber to a temperature sufficient to effect cracking. 90

4. The process of producing hydrocarbon oils having low boiling points from hydrocarbon oils having high boiling points which comprises subjecting the original oil to a continuous agitating movement within a closed series of communicating tubular chambers, causing a continuous movement of the oil lengthwise of each chamber and progressively through each chamber of the series, passing freely movable non-absorbent elements of high heat conductivity in contact with said oil and lengthwise of said chambers, and subjecting the contents of said series of chambers to a temperature sufficient to effect cracking. 95 100

5. The process of producing hydrocarbon oils having low boiling points from hydrocarbon oils having high boiling points which comprises subjecting the original oil to a continuous agitating movement within a closed series of communicating tubular chambers, causing a continuous movement of the oil lengthwise of each chamber and progressively through each chamber of the series, passing metallic balls freely movable in contact with said oil and lengthwise of said chambers, and subjecting the contents of said series of chambers to a temperature sufficient to effect cracking. 110 115

6. The process of producing hydrocarbon oils having low boiling points from hydrocarbon oils having high boiling points which comprise subjecting the original oil to a continuous agitating movement within a closed series of communicating tubular chambers and to a temperature sufficient to effect cracking, causing a continuous movement of the oil lengthwise of each chamber and pro- 120 125 130

gressively through each chamber of the series, passing freely movable non-absorbent elements having high heat conductivity in contact with said oil, and lengthwise of said 5 chambers, and subjecting the contents of said chambers to an increasing degree of heat during movement of the oil through the successive chambers involving an increase in temperature of about 200° F. from 10 the first chamber of the series to the last chamber thereof.

7. The process of producing hydrocarbon oils having low boiling points from hydrocarbon oils having high boiling points which 15 comprises subjecting the original oil to a continuous agitating movement within a closed series of communicating tubular chambers and to a temperature sufficient to effect cracking, causing a continuous movement of the oil lengthwise of each chamber and progressively through each chamber of the series, passing freely movable metallic balls in contact with said oil, and lengthwise of said chambers, and subjecting the contents 25 of said chambers to an increasing degree of heat during movement of the oil through the successive chambers involving an increase in temperature of about 200° F. from the first chamber of the series to the last chamber 30 thereof.

8. The process of producing hydrocarbon oils having low boiling points from hydrocarbon oils having high boiling points which comprises subjecting the original liquid oil 35 to a continuous agitating movement within a closed tubular system, causing the oil to move through said tubular system, moving freely movable metallic elements through said oil and lengthwise of the tubes of said 40 system, subjecting the contents of said system to an increasing degree of heat ranging from at least 550° F. at the point of introduction of the oil to an additional 200° F. at the hottest point in said system.

45 9. The process of producing hydrocarbon oils having low boiling points from hydrocarbon oils having high boiling points which comprises subjecting the original liquid oil to a continuous agitating movement within 50 a closed tubular system, causing the oil to move through said tubular system, passing freely movable metal balls through said oil and lengthwise of said system, and subjecting the contents of said system to an increasing 55 degree of heat ranging from at least cracking temperature at the point of introduction of the oil to an additional 200° F. at the hottest point in said system.

60 10. The process of producing hydrocarbon oils having low boiling points from hydrocarbon oils having high boiling points which comprises introducing oil to be treated into 65 a series of communicating horizontally arranged tubular screw conveyor retorts positioned in different levels, passing the oil and

metallic balls through each retort and progressively into and through each next adjacent retort and thus subjecting the oil to a continuous agitating and progressive movement in contact with the constantly moving 70 screw conveyor and balls, and subjecting the contents of said retorts to a temperature sufficient to effect cracking.

11. The process of producing hydrocarbon oils having low boiling points from hydrocarbon oils having high boiling points which comprises introducing oil to be treated into a series of communicating horizontally arranged tubular screw conveyor retorts positioned in different levels, passing the oil and 75 metallic balls through each retort and progressively into and through each next adjacent retort and thus subjecting the oil to a continuous agitating and progressive movement in contact with the constantly moving 80 screw conveyor and balls, and subjecting the contents of said system of tubular retorts to an increasing degree of heat ranging from at least 550° F. at the retort in which the oil is introduced to an additional 200° F. at the 85 last retort of said series.

12. The process of producing hydrocarbon oils having low boiling points from hydrocarbon oils having high boiling points which comprises introducing oil to be treated into 90 a series of communicating horizontally arranged tubular screw conveyor retorts positioned in different levels, passing the oil and metallic balls through each retort and progressively into and through each next adjacent retort and thus subjecting the oil to a continuous agitating and progressive movement in contact with the continuously moving 95 screw conveyor and balls, passing the oil and balls from the lowermost retort to the uppermost retort, and subjecting the contents of said retorts to a heat sufficient to 100 effect cracking.

13. The process of producing hydrocarbon oils having low boiling points from hydrocarbon oils having high boiling points which comprises introducing oils to be treated into a series of communicating horizontally arranged tubular screw conveyor retorts positioned in different levels, passing the oil and 110 metallic balls through each retort and progressively into and through each next adjacent retort and thus subjecting the oil to a continuous agitating and progressive movement in contact with the continuously moving screw conveyor and balls, passing the oil and balls from the lowermost retort to the uppermost retort, and subjecting the contents of said system to an increasing degree 115 of heat ranging from at least 550° F. at the uppermost retort to at least 750° F. at the lowermost retort.

In testimony whereof I affix my signature.

ROLAND B. DAY.
